(57) **CLAIM**

The ornamental design for a ballpoint pen, as shown and described.

DESCRIPTION

FIG. 1 is a Perspective View of a ballpoint pen of the present invention;

FIG. 2 is a Front Elevation View thereof;

FIG. 3 is a Rear Elevation View thereof;

FIG. 4 is a Left Side View thereof;

FIG. 5 is a Right side View thereof;

FIG. 6 is a Top Plan View thereof; and,

FIG. 7 is a Bottom Plan View thereof.
